UNITED STATES PATENT OFFICE

93,768

DESIGN FOR A FLOWER CONTAINER STAND

Edith C. Gurganus, Memphis, Tenn.

Application May 21, 1934, Serial No. 51,872

Term of patent 14 years

To all whom it may concern:

Be it known that I, EDITH C. GURGANUS, a citizen of the United States, residing at Memphis, in the county of Shelby and State of Tennessee, have invented a new, original, and ornamental Design for a Flower Container Stand, for which the following is a specification, reference being had to the accompanying drawing, forming part thereof.

Figure 1 is a front view slightly in perspective, Figure 2 is a rear view slightly in perspective, Figure 3 is a side view of a flower container stand showing my new design.

I claim:

The ornamental design for a flower container stand, as shown.

EDITH C. GURGANUS.
